3,074,352 WELL PUMP

Renic P. Vincent, Tulsa, Okla., assignor to Pan American Petroleum Corporation, Tulsa, Okla., a corporation of Delaware

Filed Mar. 3, 1961, Ser. No. 93,084
10 Claims. (Cl. 103—179)

This invention relates to a novel pump design adapted for use in the pumping of oil wells. More particularly, 10 it is concerned with a pump design especially useful in the pumping of wells formed by slim hole drilling, i.e., wells completed without tubing.

In recent years considerable interest has been shown in slim hole drilling and completions because of the 15 substantial savings in drilling and equipment costs. With the introduction of such practice, however, a number of problems have been created, one of the more important being the design of a pump capable of operating efficiently over extended periods of time under slim hole producing conditions.

Pumps for slim hole wells using hollow sucker rods as a conduit for lifting the fluid to the surface have been previously employed, but have been unsatisfactory because of the hydraulic forces inside the hollow rods which act upwardly on the bottom of the pump plunger, causing the rods to buckle helically, or to "corkscrew" on the pump downstroke.¹ Furthermore, with the rods corkscrewed on the pump downstroke, excessive wear occurs, not only on the rods but also on the conduit surrounding the hollow rods. In the case of slim hole or multizone wells, this conduit is the well casing. Excessive wear can cause holes, making expensive remedial measures necessary. During the pump upstroke, the sucker rod straightens. The repeated helical bending and straightening causes fatigue of the hollow rod connections and breakage occurs.

It is advisable, in order to eliminate the conditions which cause buckling, to lift the heavier well fluid, such as oil and/or water, up the annulus between the hollow sucker rod string and the conduit and to provide an escape to the surface for the gaseous fluids through the string of hollow sucker rods. In this system, the high hydraulic pressure on the outside of the hollow rods resulting from the head of fluid, provides a straightening force on the rods on both the upstroke and the downstroke.

There are pumps available which permit production as described above. Such equipment, however, employs a sliding crossover seal which permits gaseous fluids to flow around the pump into the hollow rods and, at the same time, transfers the fluids flowing from the variable-volume chamber of the pump into the annulus between the hollow rods and the surrounding conduit. The disadvantage of this system is that the length of the pump is doubled since the sliding seal crossover arrangement is, by necessity, located above the pump and must be of equal length to accommodate the full pump stroke. Also, the full hydraulic head of fluid is exposed to this sliding seal on both the upstroke and downstroke of the pump. This leak reduces the efficiency of the pump and will also, during long shut-down periods, allow the eduction conduit to drain.

Also, the design of these pumps has been such that sand and other solids tending to collect above the pump seat in time cause the pump to fail. A further difficulty encountered with pumps of this type is gas locking. If gas accumulates in the working barrel of a pump equipped with conventional ball-and-seat valves, there is a possi-

2

bility that the pump will gas lock. To expel the gas, the pressure in the gas zone on the downstroke must be high enough to overcome the pressure of the fluid operating on top of the valve. Only then will the valve open. If the stroke is too short, or if too much gas has accumulated, operation of the pump does nothing more than compress and expand the gas in the working barrel and no oil is lifted. Lengthening the stroke or increasing the pumping speed can be used to overcome this problem.

It is an object of my invention to provide a hollow sucker rod pump consisting essentially of a single section and in which the rod is not subjected to buckling action because during the downstroke there is no net hydraulic upward force exerted thereon. It is a further object of my invention to provide a pump capable of operating over extended periods with sand or similar solids in the pumped fluids without damage to the pump itself. It is another object of my invention to provide a pump that can handle gases and liquids simultaneously without gas locking.

For a better understanding of my invention, reference is made to the accompanying drawings in which:

FIGURE 1 is an elevational sectional view of the complete pump mechanism showing the latter in the downstroke position;

FIGURE 2 is a fragmentary sectional view, illustrating a modification of the gas-oil separator portion of the pump;

FIGURE 3 is a plan view of FIGURE 1 taken along line 3—3;

FIGURE 4 is a plan view of FIGURE 2 taken along line 4—4; and

FIGURE 5 is a sectional view of another type of valve design that may be substituted for the lower traveling valve shown in FIGURE 1.

Referring again to FIGURE 1, a well casing 10 has at the lower end thereof a pump seat 12. A pump assembly 14, including a working barrel 16 and a head 18 having ports 20, rests in pump seat 12. Guidepiece 22, which is a part of head 18, holds hollow rod 24 in alignment with the axis of the pump. The fit of rod 24 with the guidepiece need not be fluid-tight. At the lower end of rod 24, a piston or plunger 26, sized so as to slide freely within working barrel 16, is threadedly engaged to rod 24. Permissible clearance between the plunger and working barrel may range from about .0005 to about .005 inch. At the base of barrel 16 is a standing valve 28. In plunger 26 are a plurality of annularly-spaced longitudinal passages 30 which terminate at the beveled face of plunger 26, which forms a seat 32 for traveling valve 34. Stop 36 prevents further upward movement of valve 32. Above stop 36 is a second standing valve comprising an annular member 38 resting on auxiliary valve seat 40 which fits loosely about rod 24. Auxiliary valve seat 40, in turn, forms a seal with valve seat 42. Valve 38 preferably does not form a fluid-tight seal with rod 24 and auxiliary valve seat 40.

In FIGURE 2, an oil-gas separator may be substituted for plunger 26 of FIGURE 1, wherein a plunger 50 carried on rod 24 is sized to slide freely in working barrel 16. The lower end of rod 24 has a closure 52 which, with standing valve 54, forms chamber 56 having port 58 communicating with a plurality of spaced vertical passageways 60. These passageways terminate at the top side of plunger 50, having beveled face 62. Passageways 60 do not surround rod 24, but preferably are arranged in a pattern such as that shown in FIGURE 4. Also, in plunger 50, and substantially opposite passageways 60, is a single passageway 64 extending from the base of plunger 50 above closure 52 and communicating with the interior of rod 24 via port 66.

¹ See AIME Transactions, Petroleum Branch, vol. 210, pp. 73-88.

In FIGURE 5, a plunger 70, having vertical annularly disposed passageways 72, reciprocates in working barrel 16. The lower end of hollow rod 24 has an externally threaded portion 76 threadedly engaged to internally threaded portion 78 of a downwardly extending recess in plunger 70.

In operation, referring to FIGURE 1, well fluids enter pump assembly 14 through bottom standing valve 28 on the up-stroke. Gas separates from the liquids, and the bulk thereof flows upwardly into hollow rod 24. Gas breakout is assisted on the downstroke of plunger 26 which serves to agitate the liquids in the lower end of working barrel 16. During this same downstroke, liquids, together with small amounts of gas, flow upwardly through passageways 30 in plunger 26 and lift traveling valve 34 off seat 32. Stop 36 limits the distance traveling valve 34 moves along rod 24 and promotes faster closing of the valve at the start of the upstroke. Also, at this time, there is a tendency for fluids below plunger 26 to flow out the orifice, seating the valve 28, causing the latter to seat or close, thus tending to drive any remaining fluids into hollow rod 24 and into passage ways 30. On the upstroke, valve 34 seats in beveled face 32 to trap the liquid above it. The rising liquid unseats standing valve 38. After passing through the upper valve, the liquids discharge through ports 20 into the annulus between slim hole casing 10 and hollow sucker rod 24. Guidepiece 22, at the head of pump assembly 14, holds the hollow rod in alignment with the axis of the pump and improves the operation of the upper standing valve 38.

In place of the upper standing valve shown in FIGURE 1, a single element valve similar to traveling valve 34 may be used. The upper standing valve preferably does not form a fluid-tight seal between hollow rod 24 and auxiliary valve seat 42. This structure permits a small quantity of oil above the pump to leak into pump barrel 16 above the piston. By this slight leak, a gas locking condition can be corrected when enough liquid has flowed into the working barrel to unseat the upper standing valve and displace the gas via ports 20 at the top of the pump stroke. Gas locking tendencies are further reduced owing to the low head space between the piston and the upper standing valve. Where severe gas locking is not a problem, the upper valve may be close-fitting to prevent leak-back. Also, the bottom standing valve may be omitted with the close-fitting valve because the oil in the casing will not leak out through the pump during shut in periods.

As previously indicated, a modification such as that shown in FIGURE 2 may be substituted for the plunger design of FIGURE 1. Gas and oil in working barrel 16 below plunger 50 separate, with the gas rising through passage 64 and entering hollow rod 24 via port 66 above closure 52. The well liquids pass through standing valve 54 in rod 24, flow through the rod via port 58 and passages 60 into working barrel 16 above the plunger. Above plunger 50 the pump structure employing the modification shown in FIGURE 2 may be identical with that illustrated in FIGURE 1.

A further modification of a suitable plunger structure is shown in FIGURE 5 in which well fluids enter the open end of working barrel 16, separated gas being vented up hollow rod 24. Well liquids on the downstroke travel upwardly through passages 72 in plunger 70, unseating ball valves 74 and filling the annulus between barrel 16 and rod 24. On the upstroke of plunger 70, valves 74 close carrying annulus liquids upwardly through the barrel into an upper structure which may again resemble that shown in FIGURE 1.

By the foregoing description and drawings, it will be apparent to those skilled in the art that the present invention provides a simple and efficient slim hole well pump capable of handling gases and liquids. While this pump mechanism is designed specifically for slim hole wells having small diameter pipe cemented in the well, it

will be apparent that the principles illustrated by the design described herein will be applicable to many other environments without departing from the scope of this invention.

I claim:

1. A pump having in combination a barrel, a hollow rod member extending into said barrel, a guidepiece at the upper end of said barrel adapted to hold said rod member parallel and concentric with the longitudinal axis of said barrel while said rod member reciprocates therein, a plunger in said barrel, said rod member carrying said plunger and communicating with the remote side of said plunger, valve means in said barrel spaced above said plunger and defining a variable-volume chamber therebetween,

an outlet communicating with said chamber and with the space between said hollow rod and said guidepiece, communication through said outlet being controlled by said valve means, passage means in said plunger for the flow of fluids through said plunger, and means on the side of said plunger adjacent said chamber for preventing the downward flow of liquids through said plunger on the upstroke of said plunger.

2. The pump of claim 1 in which said last named means comprises a travelling valve on said rod member which prevents the downward flow of liquids through said plunger, said travelling valve being adapted to form a fluid-tight seal with said plunger only on the upstroke of said plunger.

3. The pump of claim 2 in which said rod member carries a stop between said travelling valve and the valve means cooperating with said outlet.

4. The pump of claim 1 in which said plunger has a plurality of spaced passages running through said plunger and into said chamber.

5. The pump of claim 1 in which there is a valve means in the lower end of said barrel on said remote side of said plunger, said valve means being adapted to open on the upstroke and close on the downstroke of said pump.

6. The pump of claim 1 in which said outlet means comprises a valve seat between said variable-volume chamber and said guidepiece and a standing valve on said rod member adapted to form a seal with said seat.

7. In a pump, the combination comprising a barrel, a hollow rod member extending into said barrel, a guidepiece at the upper end of said barrel adapted to hold said rod member parallel with the longitudinal axis of said barrel while said rod member reciprocates therein, outlet means in said guidepiece,

a plunger in said barrel having an outside diameter slightly less than the inside diameter of said barrel, said rod member carrying said plunger and communicating with the remote side thereof,

a valve seat in said barrel cooperating with said outlet means spaced above said plunger and a standing valve surrounding said rod member adapted to form a seal with said valve seat to define a variable-volume chamber between said valve seat and said plunger, passage means in said plunger for the flow of fluids through said plunger,

means on the side of said plunger adjacent said chamber for preventing the downward flow of said liquids through said plunger on the upstroke of said plunger.

8. A pump having in combination a barrel, a hollow rod member extending into said barrel, a plunger in said barrel, said rod member carrying said plunger and communicating with the remote side of said plunger, valve means in said barrel spaced above said plunger

and defining a variable-volume chamber therebetween,
an outlet communicating with said chamber and with
the exterior of said chamber, communication through
said outlet being controlled by said valve means,
passage means in said plunger for the flow of fluids
through said plunger, and
means on the side of said plunger adjacent said cham-
ber for preventing the downward flow of liquids
through said plunger on the upstroke of said plun- 10
ger.
9. In a pump, the combination comprising a barrel,
a hollow rod member extending into said barrel, a
plunger in said barrel and carried by said rod mem-
ber, the latter communicating with the remote side 15
of said plunger,
valve means in said barrel spaced above said plunger
and defining a variable-volume chamber therebe-
tween,
an outlet communicating with said chamber and with 20
the exterior of said chamber, communication
through said outlet being controlled by said valve
means,
passage means in said plunger for the flow of fluids 25
through said plunger, and
a check valve associated with said plunger for prevent-
ing the downward flow of liquid through said plunger
on the upstroke of said plunger.
10. In a pump, the combination comprising a barrel, 30
a hollow rod member extending into said barrel,

a plunger in said barrel and carried by said rod mem-
ber, the latter communicating with the remote side
of said plunger,
valve means in said barrel spaced above said plunger
and defining a variable-volume chamber therebe-
tween,
an outlet communicating with said chamber and with
the exterior of said chamber, communication through
said outlet being controlled by said valve means,
a passage means (1) in said plunger communicating
with the interior of said rod member and with said
remote side,
a conduit leading into said plunger from said remote
side,
a passage means (2) leading from said conduit through
said plunger and into said variable-volume chamber,
and
a check valve in said conduit for preventing the down-
ward flow of liquids through said plunger on the
upstroke of said plunger.
